CLAIM

The ornamental design for a handpiece for laser fiber optic delivery system, as shown.

DESCRIPTION

FIG. 1 is a front, right perspective view of the handpiece for laser fiber optic delivery system showing our new design;

FIG. 2 is a right side view thereof;

FIG. 3 is a bottom view thereof;

FIG. 4 is a top view thereof;

FIG. 5 is a left side view thereof;

FIG. 6 is a front view thereof; and,

FIG. 7 is a rear view thereof.
